(57) **CLAIM**

The ornamental design for a refrigerant distributor, as shown and described.

DESCRIPTION

FIG. 1 is a perspective view of a refrigerant distributor showing our new design.

FIG. 2 is another perspective view thereof.

FIG. 3 is a front view thereof.

FIG. 4 is a rear view thereof.

FIG. 5 is a top view thereof, a bottom view being a mirror image of the top view; and,

FIG. 6 is a left side view thereof, a right side view being a mirror image of the left side view.

The broken lines shown herein are for illustrative purposes only and form no part of the claimed design.

1 Claim, 5 Drawing Sheets
